(57) **CLAIM**

We claim the ornamental design for an air pump cart, as shown and described.

DESCRIPTION

FIG. 1 is a front perspective view of an air pump cart showing our new design;

FIG. 2 is a front view of the claimed design of FIG. 1;
FIG. 3 is a rear view of the claimed design of FIG. 1;
FIG. 4 is a left side view of the claimed design of FIG. 1;
FIG. 5 is a right side view of the claimed design of FIG. 1;
FIG. 6 is a top view of the claimed design of FIG. 1; and,
FIG. 7 is a bottom view of the claimed design of FIG. 1.
The ornamental design which is claimed is shown in solid lines in the figures. The broken lines in the figures are for the purpose of illustrating portions of the air pump cart that form no part of the claimed design.
